UNITED STATES PATENT OFFICE.

CLARENCE S. DAVIS, OF BUFFALO, NEW YORK.

RAILWAY-TRACK CONSTRUCTION.

1,409,526.

Specification of Letters Patent. Patented Mar. 14, 1922.

Application filed October 7, 1920. Serial No. 415,241.

To all whom it may concern:

Be it known that I, CLARENCE S. DAVIS, a citizen of the United States, residing at Buffalo, in the county of Erie and State of New York, have invented certain new and useful Improvements in Railway-Track Constructions, of which the following is a specification.

My invention relates to improvements in railway track constructions, and more particularly to rail joints and ties therefor.

The primary object of my invention is the provision of a rail joint wherein the use of all bolts is dispensed with, and wherein the joint members are adapted for use with the usual rail ends having elongated bolt holes therethrough.

Another object of my invention is the provision of a joint of this kind, which will prevent relative upward and downward movement of the rail ends connected thereby.

Another object is to provide a rail joint whereby the rail ends can be quickly and rigidly connected together without resorting to the use of bolts and wrenches for applying nuts to the bolts.

A further object is to provide a track construction in which a metallic tie is embodied which is constructed to provide a yielding rail support or, in other words, furnish a cushion for the rails so as to overcome the objection to the rigidity of metallic ties heretofore designed.

A further object is to provide a metallic tie with removable end-thrust bearing members so that when employed at curved parts of a track they may have said end-thrust bearing members connected thereto at the outer side of the curve to counteract the tendency of the tie moving lengthwise.

A further object of my invention is to provide the fish plates of the rail joint with parts interlocking with said tie.

A still further object is to provide a tie especially adapted for co-action with my improved rail joint, one which can be rolled to form, and by means of suitable punching presses shaped and provided with notches or openings to receive parts of the fish plates.

A still further object is to provide a boltless joint so constructed that the rails can contract and expand under different temperatures while maintaining a solid bearing against the tie and so that relative movement of the rail ends upwardly and downwardly is prevented, thereby greatly lessening

clicking or hammering noise when trains pass over the rails.

With these and other objects in view, the invention consists in the novel features of construction and in the arrangement and combination of parts to be hereinafter described and more particularly pointed out in the subjoined claims.

In the drawings:

Fig. 1 is a plan view of a portion of a track having the rails and the ties broken.

Fig. 2 is a transverse section taken on line 2—2, Fig. 1.

Fig. 3 is an enlarged transverse section taken on line 3—3, Fig. 1.

Fig. 4 is a detached perspective view of the removable end thrust bearing member.

Fig. 5 is an enlarged transverse section taken on line 5—5, Fig. 1.

Fig. 6 is a longitudinal section taken on line 6—6, Fig. 5, looking in the direction of the arrow crossing said line.

Fig. 7 is a longitudinal section taken on line 7—7, Fig. 3, looking in the direction of the arrow crossing said line, a portion of the fish plate at the end thereof being broken away.

Fig. 8 is a detached perspective view of one of the retainer pins whereby the fish plates or joint members are retained in position on the tie and against the rail.

Fig. 9 is a longitudinal section taken on line 9—9, Fig. 7.

Fig. 10 is a transverse section taken on line 10—10, Fig. 3.

Fig. 11 is a perspective view of one end of my improved tie.

Fig. 12 is a detached perspective view of one of the fish plates or joint members.

Fig. 13 is a perspective view of one of the fish plates or joint members inverted.

Reference being now had to the drawings in detail in which like numerals indicate like parts throughout the several figures, the numeral 14 designates my improved rail-tie employed at joints of the rails, and 15 the usual ties employed between rail joints.

While I have shown wooden ties between my improved metallic ties employed at the rail joints, it is to be understood that where desired, my improved ties may be substituted throughout a track for the usual wooden ties now commonly in use.

16 designates the rails, adjoining lengths abutting or being placed end to end, as at 17,

My improved tie is so constructed that it may be rolled and therefore is comparatively cheap and more durable than metallic ties which are cast. Throughout the major portion of its length, each metallic tie is substantially of I-formation in cross section, as best shown in Fig. 6, it being provided with an upper bearing portion 18, a supporting portion 19 adapted to rest firmly and evenly on the road bed, and a connecting web 20. At one end the upper or bearing member 18 is widened, as clearly shown at 21, and on this widened end the ends of adjoining rails are adapted to rest.

When rolling the tie member, the upper bearing member may be rolled to the width of the large end throughout the length of the tie, and portions may be punched or stamped from the wide upper bearing member as rolled, to reduce the width of the same so as to conform to the width of the lower or supporting member 19, which is of even width throughout its length.

As the joints of the rails forming the track are out of transverse alignment, the joints of one rail being invariably midway between the joints of the other, a wide bearing will not be required at both ends of the tie; consequently the ties are reversed so that alternately the wide ends thereof are at the same side of the track, as clearly shown in Fig. 1.

At both the wide and narrow ends of the tie, the upper or bearing member 18 is provided with two series of openings 22, each series being arranged transversely of the tie, and the two series at each end are so spaced that the space between them approximates the width of the base of the rail which lies transversely over and receives bearing from the tie between said two series of openings. These openings are preferably oblong with their length in the direction of the length of the tie, and along the outside of each series of openings is a second series of openings 23, each series being also arranged transversely of the tie, and the openings of each series being oblong with their length preferably transversely of the tie. The openings 22 may be termed loop openings or loop-receiving openings, while the openings 23 may be termed clip or hook-receiving openings.

The joint-members or fish plates 24 employed at the wide ends of the ties are exact counterparts, as clearly shown in Figs. 1 and 3, and each is substantially of a length conforming to the width of the wide portion of the upper or bearing member 18 of the tie. Each joint or fish member comprises two angular parts 25, 26, the part 25 lying against the web of the rail while the part 26 bears against the base of the rail and against the upper surface of the tie, said part 26 being offset, as at 27. The portion of the part 26 outside of said offset is at a right angle

to the part 25, while the portion between the offset and said part 25 is at a slight angle to the outer portion of the part 26 and at an acute angle to the part 25, this formation being to assure complete bearing of the part 25 against the web of the rail and complete bearing of the part 26 against the base of the rail and the upper surface of the tie within a certain region along said rail.

The part 26 has loops 28 stamped or otherwise formed therefrom, which loops extend downwardly and are passed through the openings 22. Along the outer edge of each bearing member or fish plate, angular clips or hooks 29 are provided, these hooks extending downwardly and preferably at a slight angle from the outer edge of the part 25, as at 30, and thence outwardly parallel with the outer portion of said part 26, as at 31. These hooks are passed through the openings 23 in the tie so that the downwardly bent portions 30 are within said openings and the outwardly-directed extremities 31 lie underneath and bear against the under side of the upper or bearing portion 18 of the tie, as clearly shown in Fig. 3. Each of the parts 25, which may be termed a web bearing part by reason of its bearing against one side of the web of the rail, has a series of nubs or pins 32 extending therefrom, these nubs or pins being entered into the usual bolt openings 33 provided in the rail webs at the ends thereof. Said bolt holes, as shown in Fig. 7, are slightly elongated so that when the rails are secured to the tie they may expand or contract while the nubs or pins 32 of the opposite joint members or fish plates are entered therein from opposite sides, as clearly shown in Fig. 3.

The ends of two adjoining rails are positioned in place across the wide end of the tie and the joint members or fish plates 24 are then connected to the tie by inserting the hooks 29 through the openings 23 of the tie and swinging said joint members or fish plates inwardly and downwardly to pass the loops 28 through the openings 22 in the tie. When properly positioned, these joint members or fish plates have the parts 26 bearing firmly against the base of the rail and against the upper surface of the tie outside of said base, while the parts 25 are brought firmly against the web of the rail and have their nubs or pins 32 entered into the bolt holes 33 of the rails from opposite sides thereof, the upper edges of the parts 25 being in contact with the under sides of the heads of the rails, as clearly shown.

By providing the joint members or fish plates with web bearing portions, such as 25, the rails are held against outward or inward movement and retained in perfect alignment. Underneath the rail and the joint members or fish plates, the web 20 of

the tie is cut away, as at 34, and this cut away portion or opening is of considerable length. The upper or bearing member 18 of the tie directly above this opening is therefore permitted to flex slightly under weight so that a cushioning effect is provided within the construction of the tie, which is found absolutely necessary in railway track construction, for purposes well understood.

- 10 The joint members or fish plates 24 are retained in position by means of retainer pins 35, which are inserted through the loops 28 thereof underneath the upper or bearing member 18, said pins being firmly retained in the bight of the loop and bearing against the under side of said upper or bearing portion 18. At one end each pin is provided with an enlargement or head 36, which bears against the outer edge of one 20 of the end loops of the series passing through the series of openings 22 while the other end of said pin is split, as at 37, and projects outwardly beyond the opposite end loop of the series, said split portion being bent, as 25 at 38, with opposite side portions thereof bearing against the edge of said last-mentioned loop. In this manner the joint members or fish plates are securely retained in position without the use of nuts or bolts. 30 The yielding movement of that portion of the upper or bearing member 18 spanning the opening 34 in the web of the tie compels abutting ends of the rails to yield together, thus giving assurance that when the wheels 35 of a car or locomotive pass over the end of one rail any slight depression of said end will cause the end of the abutting rail to yield with it, thereby greatly lessening the clicking or hammering noise usually made when 40 wheels travel over rail joints. Such independent upward and downward movements of the ends of adjoining rails is further objectionable for the reason that the ends of the rails become quickly rounded and after 45 a time a decided depression will be formed in the rail at each of the joints.

The joint members or fish plates at the narrow end of each tie are secured to the tie in identically the same manner as provided for securing the joint members or fish plates at the wide end of the tie. The outer joint member or fish plate bearing against the outer side of the rail at the narrow end of the tie is constructed exactly like the joint members or fish plates at the wide end of the tie, except that it is made narrower to conform to the width of the narrow end of the tie and is not provided with the nubs or pins 32 shown on the joint members or fish plates at the wide end of the tie, for the reason that this joint member or fish plate bears against an imperforate portion of the rail. The joint member or fish plate at the inner side of the rail is not provided with 65 the vertical web-bearing portion 25 and

therefore has only the part corresponding to the part 26 of the joint members or fish plates at the wide end of the tie. I have, however, designated the portions of the joint members or fish plates at the narrow end of the tie with the same numerals of reference applied to like portions of the joint members or fish plates at the wide end of the tie.

The joint member or fish plate at the narrow end of the tie, which is applied to the outer side of the rail need not have the vertical web-bearing portion where the rail is straight, but where the rail is curved it would be advisable to provide it with the web-bearing portion 25 at the outer side of the curve. The pins 35 are of course inserted through the loops of the joint members or fish plates at the narrow end of the tie in the same manner as provided for to secure the joint members to the tie at the wide end of the latter.

As clearly shown in Fig. 2 of the drawings, the web 20 of the tie is somewhat shorter than the top or bearing member 18 and the bottom or supporting member 19, and near each end of said web it is provided with openings 39. When a tie is used along a curved portion of a track, an end-thrust bearing member 40 is removably secured to the tie at the outer side of the curve. This bearing member comprises a flat member 41 with two spaced flanges 42 extending inwardly therefrom, the space between said flanges being adapted to receive the end of the web 20 of the tie. The flanges 42 have openings 43 therein, which register with the openings 39 in the web 20 of the tie, and through these registering openings, split pins 44 are passed.

If desired, the end-thrust bearing member may be secured to each end of all of the ties, regardless of whether the track is curved or straight-lined. Where, however, the bearing member is not used, the openings 39 in the web of the tie serve no purpose.

I have herein shown joint members or fish plates adapted to be stamped from sheet material with the loops 28 stamped from the body of the material, and the clips or hooks 29 formed by cutting out the material along one of its marginal portions and bending the projecting portions, so formed, into hook shape, but it is to be understood that these bearing members or fish plates may be cast or otherwise constructed.

It is to be noted that there are no parts of the device projecting prominently from the rail or tie, and therefore there will be no obstructions presented to rolling stock moving over the rails and particularly to the operating parts of snow plows.

While I have shown and described what I now consider the preferred construction of the principles involved in this invention,

I desire it to be understood that modifications may be resorted to without departing from my invention or sacrificing any of the advantages thereof.

5 Having thus described my invention, what

I claim is:-

1. A metallic tie having a flat bearing member, a flat supporting member spaced from said bearing member and a web connecting said bearing and supporting members, said web having openings therein extending from said flat bearing portion downwardly and over which rails are adapted to rest.

15 2. A tie having two horizontal spaced members and a web connecting said spaced members, said web terminating at one end short of said horizontal members and having an opening at said end, a detachable end-

20 thrust bearing member provided with an opening adapted to register with the opening in said web, and a pin passing through said registering openings for securing said end-thrust bearing member to said web.

25 3. A tie having two spaced horizontal members and a web or vertical member connecting said horizontal members and terminating at one end short of said horizontal members, an end-thrust bearing member having a flange extending inwardly therefrom adapted to lie against said web, and means for securing said flange to said web.

4. A tie having two spaced horizontal members and a web connecting said horizontal members and terminating at one end short of said horizontal members, an end-thrust bearing member comprising a transverse portion and spaced flanges extending inwardly from said transverse portion, said flanges being adapted to lie against opposite sides of said web and said web and flanges having registering openings, and a pin passing through said registering openings for securing said end-thrust bearing member to said web.

45 5. The combination of a tie having openings therein, a rail lying crosswise on said tie and positioned between said openings, fish plates bearing against opposite sides of said rail and against the upper surface of said tie and having hooks hooking into the openings of said tie, and means concealed underneath the surface of said tie for rigidly retaining said fish plates in position.

55 6. The combination with a tie having two transverse series of openings, a rail adapted to rest transversely on said tie between said two series of openings, fish plates bearing against said rail and tie and having hooks adapted to be hooked into said openings, and means for retaining said fish plates to said rail and tie.

65 7. The combination of a tie having a transverse series of openings therein, a rail

adapted to rest transversely upon said tie, and a fish plate having loops extending downwardly therefrom, said loops being passed through said openings, and a pin extending through said loops to retain the fish plate in position.

8. The combination of a tie having a flat bearing member at the top and two transverse series of openings through said flat bearing member, a rail resting transversely on said tie between said two series of openings, fish plates bearing against said rail and said tie and having loops extending through said openings and projecting beneath the flat bearing member of said tie, and a pin passing through the loops of each fish plate between the bights of said loops and the under side of said flat bearing member.

85 9. The combination of a tie having a flat bearing member provided with two transverse series of loop-receiving openings and two transverse series of hook-receiving openings between which said loop-receiving openings are located, a rail resting transversely on said flat bearing member between said loop-receiving openings, a fish plate at each side of said rail resting thereagainst and upon said flat bearing member and having hooks passed through said hook-receiving openings and loops passed through said loop-receiving openings, and pins passed through said loops underneath said flat bearing member.

95 10. The combination with a tie, of a rail having adjacent ends of two rails resting on said tie, the webs of each rail having elongated holes, fish plates at opposite sides of said rails having pins thereon extending into said holes from opposite sides, and pin and loop connection between said fish plates and said tie.

110 11. The combination of a tie having a flat bearing member provided with loop-receiving openings and a web extending downwardly from said flat bearing member and having an opening therein, rails having the adjacent ends thereof resting upon said flat bearing member directly over the opening in said web, fish plates provided with downwardly projecting loops extending through the loop-receiving openings of said flat bearing member and projecting beneath the under surface of the latter, and pins passed through said loops and through the opening in said web.

115 12. The combination of a tie having a flat bearing member provided with two spaced transverse series of openings and a web extending from said flat bearing member and having an opening therethrough, rails having the adjacent ends thereof resting upon said flat bearing member between the openings therein and above the opening in said web, fish plates bearing against said rails

and against the upper surface of said flat bearing member, said fish plates having a series of loops passing through the openings in said flat bearing member, and pins 5 passing through said loops underneath said bearing member and bearing against the latter, each pin having a head at one end and being split at its other end with the split portions thereof bent to prevent removal of 10 said pins from said loops.

13. The combination of a tie having a flat bearing member provided with two transverse series of hook-receiving openings and two transverse series of loop-receiving openings between said two series of hook-receiving openings and having also a web extending downwardly from said flat bearing member provided with an opening extending the full range of the openings in said flat bearing member, a rail resting upon said flat bearing member between said hook-receiving openings, fish plates bearing against said rail and against the upper surface of said flat bearing member, said fish plates having 20 hooks along one edge passed through the hook-receiving openings of said flat bearing member and bearing against the under side of the latter and loops extending through

said loop-receiving openings and projecting beneath the under surface of said bearing 30 member, and a pin passing through the loops extending through each series of loop-receiving openings and also through the opening in said web.

14. A metallic tie having a flat bearing 35 member against which two rails are adapted to rest, and a web at right angles to said bearing member having openings underneath said bearing member extending from the latter downwardly. 40

15. A metallic tie having a flat bearing member on which two rails are adapted to rest, and a web extending lengthwise along said bearing member and supporting the same, said web having openings therein to 45 provide unsupported portions for said bearing member underneath the rails resting thereon.

16. A metallic tie comprising a flat bearing member and a web, said web being disconnected from said flat bearing member along regions near each end thereof to provide portions capable of flexing on which rails are adapted to rest. 50

In testimony whereof I affix my signature. 55
CLARENCE S. DAVIS.
